MARIO A. BOET, OF HOLLIS, NEW YORK

SEPARATING AND DEFINING STRIP FOR TERRAZZO FLOOR SECTIONS

Application filed March 1, 1929. Serial No. 343,613.

This invention relates, generally, to improvements in separating and defining strips for terrazzo floor sections; and the invention has reference, more particularly, to a novel construction of separator strip for defining the shape and pattern of assembled terrazzo floors, and which is adapted to be embedded in the floor material to divide the same into sections of desired form or pattern, and in such manner as to interlock adjoining sections together, while at the same time preventing the formation and spreading of fissures or cracks in the finished flooring.

The invention, having the general objects above stated, has for a further object to provide a novel construction of strip having a novel form of interlock lugs or tongues integrally connected therewith, whereby not only is the strip held against shifting in any direction, i. e. vertically, longitudinally or laterally, from operative position relative to the floor material, but is further maintained in interlocked relation both with the underbed or screed coat section of the flooring material as well as with the terrazzo material itself. To this end said lock lugs or tongues, which are struck out of the body of the strip to project from opposite sides thereof, are of a peculiar angular construction, having a main body lying in a plane oblique to the longitudinal axis of the strip, and spur downwardly directed from the high end of said main body to embed itself in both the underbed and terrazzo material so as to fix the strip against longitudinal shifting, while the main body which also embeds itself in both the underbed and terrazzo material is adapted to prevent both lateral and vertical shifting of the strip.

Other objects of this invention, not at this time more particularly enumerated, will be clearly understood from the following detailed description of the same.

An illustrative embodiment of this invention is shown in the accompanying drawings, in which:

Fig. 1 is a perspective view of a terrazzo flooring broken away in part to show the novel separating and defining strip of this invention assembled therewith; Fig. 2 is a fragmentary view, showing in part a section

through the flooring, and in part a side elevation of the separating and defining strip embedded therein; Fig. 3 is a fragmentary view of the novel strip; Fig. 4 is a transverse section, taken on line 4—4 in Fig. 2; and Fig. 5 is a fragmentary perspective of the novel strip.

Similar characters of reference are employed in all of the hereinabove described views, to indicate corresponding parts.

In the laying of terrazzo floors an underbed of mixed sand and cement is first spread on the base flooring to the required thickness. While the underbed material is still soft or plastic, the novel separating and defining strips are inserted edgewise into the underbed, to block the same off into sections of the desired shape.

As shown in the drawings, the reference character 6 indicates the body of the separating and defining strip which is a thin flat strip of suitable metal such as brass having a continuous unbroken upper edge 7 and a corresponding unbroken lower edge 8. The metal of the separating and defining strip is flexible and, owing to the thinness of these strips, they may be transversely bent into circular or other forms when desired, to thereby define floor sections having various outlines. The strip has a vertical depth 70 when installed that is substantially equal to the combined height of the under or screed layer 9 and the finishing or terrazzo layer 10 of the flooring material, the upper edge of the strip serving to define the surface level of 75 the finishing layer. To this end the strip is pressed into the screed layer while that layer is in a semi-plastic condition, with the upper portion of the strip extending above the upper surface of the screed layer to a height 80 equal to the desired thickness of the finishing or top layer.

The body 6 of the strip is formed substantially midway of its height with spaced integral outstruck interlock lugs or tongues 85 each of which comprises a main body 12 lying in a plane oblique to the longitudinal axis of the strip and a spur or depending portion 13 extending vertically downward from the upper end of said main body. interlock lugs project from one side of the strip while others of these lugs project from the other side thereof. Preferably alternate interlock lugs project outwardly from opposite sides of the strip and are oppositely arranged so that the oblique plane of one main body 12 intersects the oblique plane of the next succeeding main body, as will be apparent from an inspection of the drawings. This is important, as this arrangement causes each succeeding pair of interlock lugs to retain the portion of the strip extending between them in fixed centered position with respect to the adjacent floor sections having layers 9 and 10. The main bodies 12 of each successive pair of lugs form, in effect, opposite side portions of a keystone or wedge-shaped interlock between the strips and the layers 9 and 10 at opposite sides of the strip, thereby securely interlocking the strip with the adjacent floor sections.

In setting the strip into the screed layer, the lower portions of the main body 12 and spur 13 of each interlock lug enters the screed layer 9. Also, the material of the screed layer enters the openings 14 made in the body 6 of the strip at the time of pressing out the interlocking lugs. The material of the screed layer contacting with the surfaces of the interlock lugs and with the edge of the openings 14 acts to hold the strip in position while the top, or finishing layer material is being placed upon the screed layer and against the strip. It will be noted that the surfaces of the interlock lugs and the edges of the openings 14 are so disposed as to positively lock the strip in fixed position with respect to the screed layer. Thus the upper and lower inclined surfaces of the main body of each interlock lug acts to prevent any relative vertical or longitudinal movement of the strip, while the surfaces of each spur 13 act to assist in preventing longitudinal movement of the strip with respect to the floor layer. The inclined outer edges of these members act to prevent relative transverse movement of the strip with respect to the floor layer. Also the lower edges of the openings 14 act to aid in preventing upward movement of the strip.

While the material forming the finishing layer is being applied to the screed layer, such material is tamped along the sides of the strip and enters and fills the openings 14 as well as completely surrounds the upper portion of the interlock lugs. These lugs being partially embedded in the screed layer, firmly hold and support the strip during this operation and prevent any movement thereof. Since the material of adjacent sections of both the screed and terrazzo layers of the flooring extend through the openings 14, such sections are firmly locked together at each of these openings. It will be noted that the upper and lower surfaces of the main body of the interlock lugs form wedge-shaped locks with adja-

cent sections of floor material, and securely hold such sections in place and prevent uneven drying thereof which would tend to cause cracks or fissures extending along the junction of the strip with the sections. Also the inclined outer edges of the interlock lugs prevent lateral displacement of the strip with respect to the adjacent sections.

The body 6 of the strips extending in one direction are notched at intervals to interlock with similar strips extending crosswise of the first strips as is clearly apparent from an inspection of Fig. 1.

Thus it will be apparent that in a completed floor the novel separating strips of this invention are not only securely fixed in interlocked relation to adjacent floor sections but are designed to tie such sections as well as the floor layers securely together into a unitary whole.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. A separating and defining strip adapted for use as a pattern and guide in laying flooring and other surfaces adapted to have a screed layer and a terrazzo or similar finishing layer comprising, a flat body having uninterrupted straight upper and lower edges, and a series of spaced interlock lugs struck outwardly from said body, said lugs having a main body extending angularly to the longitudinal axis of said strip, and a spur formed on the upper edge of said main body and extending downwardly therefrom.

2. A separating and defining strip adapted for use as a pattern and guide in laying flooring and other surfaces adapted to have a screed layer and a terrazzo or similar finishing layer comprising, a flat body having uninterrupted straight upper and lower edges, and a series of spaced interlock lugs struck outwardly from said body, said lugs having a main body extending angularly to the longitudinal axis of said strip, and a spur formed on the upper edge of said main body and extending downwardly therefrom, said interlock lugs being adapted to be embedded in interlocked relation with both said screed and said terrazzo layers.

3. A separating and defining strip adapted for use as a pattern and guide in laying flooring and other surfaces adapted to have a screed layer and a terrazzo or similar finishing layer comprising, a flat body having uninterrupted straight upper and lower edges, and a series of spaced interlock lugs struck outwardly from said body, and positioned to

- extend on opposite sides thereof, substantially from the central portion of said strip, said interlock lugs having oblique faces adapted to engage the screed and terrazzo floor layers. 5
4. A separating and defining strip adapted for use as a pattern and guide in laying flooring and other surfaces adapted to have a screed layer and a terrazzo or similar finishing layer comprising, a flat body having uninterrupted straight upper and lower edges, and a series of spaced interlock lugs struck outwardly from said body, and positioned to extend on opposite sides thereof, substantially from the central portion of said strip, said interlock lugs having oblique faces adapted to engage the screed and terrazzo floor layers, the oblique faces of each pair of successive lugs lying in intersecting planes whereby said pairs of lugs form keystone shaped interlocks 10 with adjacent floor sections. 15
5. A separating and defining strip adapted for use as a pattern and guide in laying flooring and other surfaces adapted to have a screed layer and a terrazzo or similar finishing layer comprising, a flat strip like body having a series of spaced interlock lugs struck outwardly from the sides thereof, each of said lugs having a main body extending obliquely to the longitudinal axis of said strip, said strip 20 having apertures contiguous to said lugs and being adapted to be embedded in the screed and terrazzo floor layers so that both floor layers surround portions of said main body in interlocking relation and also extend through 25 said apertures. 30
6. A separating and defining strip adapted for use as a pattern and guide in laying flooring and other surfaces adapted to have a screed layer and a terrazzo or similar finishing layer comprising, a flat strip like body having a series of spaced interlock lugs struck outwardly from the sides thereof, each of said lugs having a main body extending obliquely to the longitudinal axis of said strip and a 35 spur depending vertically from said main body, said strip having apertures contiguous to said lugs and being adapted to be embedded in the screed and terrazzo floor layers so that both floor layers surround portions of said 40 main body and said spur in interlocking relation and also extend through said apertures. 45
7. A separating and defining strip adapted for use as a pattern and guide in laying flooring and other surfaces adapted to have a screed layer and a terrazzo or similar finishing layer comprising, a flat strip like body having a series of spaced interlock lugs struck outwardly from the sides thereof, each of said lugs having a main body extending obliquely 50 to the longitudinal axis of said strip and having a curved outer edge and a spur depending vertically from the upper edge of said main body and also having a curved outer edge, said strip having apertures contiguous to said 55 lugs and being adapted to be inserted in the 60
- flooring so that the lower portions of the main body and spur of certain of said lugs are embedded in the screed layer of one floor section, whereas the lower portions of the main body and spur of others of said lugs are embedded in the screed layer of an adjacent floor section. 70
8. A separating and defining strip adapted for use as a pattern and guide in laying flooring and other surfaces adapted to have a screed layer and a terrazzo or similar finishing layer comprising, a flat strip like body having a series of spaced interlock lugs struck outwardly from the sides thereof, each of said lugs having a main body extending obliquely to the longitudinal axis of said strip and having a curved outer edge and a spur depending vertically from the upper edge of said main body and also having a curved outer edge, said strip having apertures contiguous to said lugs and being adapted to be inserted in the flooring so that the lower portions of the main body and spur of certain of said lugs are embedded in the screed layer of one floor section, whereas the lower portions of the main body and spur of others of said lugs are embedded in the screed layer of an adjacent floor section, the upper portions of the main body and spur of each of said lugs being embedded in the terrazzo layer of its respective floor section. 80
- In testimony, that I claim the invention set forth above I have hereunto set my hand this 90 13th day of February, 1929. 95
